UNITED STATES PATENT OFFICE.

EDWIN KAIN, OF CAMDEN, NEW JERSEY.

WASHING-MACHINE.

SPECIFICATION forming part of Letters Patent No. 576,198, dated February 2, 1897.

Application filed May 24, 1894. Serial No. 512,354. (No model.)

To all whom it may concern:

Be it known that I, EDWIN KAIN, a citizen of the United States, residing at Camden, in the county of Camden and State of New Jersey, have invented a new and useful Washing-
Machine, of which the following is a specification.

The invention relates to improvements in washing-machines.

10 The object of the present invention is to improve the construction of washing-machines and to provide a simple and comparatively inexpensive one capable of rapidly and thoroughly washing clothes without injury to the fabrics.

15 The invention consists in the construction and novel combination and arrangement of parts hereinafter fully described, illustrated in the accompanying drawings, and pointed out in the claims hereto appended.

20 In the drawings, Figure 1 is a perspective view of a washing-machine constructed in accordance with this invention. Fig. 2 is a longitudinal sectional view. Fig. 3 is a transverse sectional view. Fig. 4 is a detail sectional view illustrating the manner of yieldingly supporting the stationary rubber.

25 Like numerals of reference indicate corresponding parts in all the figures of the drawings.

30 1 designates a washing-machine body provided with legs 2 and having a curved sheet-metal bottom 3 to enable the water necessary for washing to be maintained at the desired temperature by means of any suitable heating apparatus, such as an oil-stove (not shown) or the like. Within the washing-machine body is arranged a stationary rubber 4, having a curved convex lower face to fit 35 snugly against the bottom of the body, but it is held out of contact with the same by means hereinafter described. The stationary rubber is provided with a concave rubbing-surface and is composed of corrugated slats 5, attached to longitudinal strips 4, the latter being recessed or notched in their lower edges, forming shoulders 6 at their ends, which rest upon the end portions of the springs 7 and operate in the recesses 9. The springs 40 5 are secured to cleats 8, which are arranged within the washing-machine body at the ends thereof, and they are provided at their ends

with recesses 9 to permit the said shoulders 6 to move upward and downward on the springs. The springs are secured intermediate of their ends, which are free to support the stationary rubber.

45 An octagonal rubbing-cylinder 10 co-operates with the stationary rubber, and is provided at its periphery with corrugations 60 formed by grooved strips. The rubbing-cylinder is mounted on a shaft 12, which is journaled in bearing-slots 13 and 14 and has vertical movement therein, the slots forming open bearings to enable the shaft and the 55 rubbing-cylinder to be readily removed from the body when the operation of washing has been completed. The bearing-slots 13 and 14 of the sides of the body form ways for the journals of the roller and permit the same to 60 move up and down during the operation of washing.

65 The bearing-slot 13 is closed at the outer face of the adjacent side by a plate 15, and ways 16 are arranged on the inner face of the 70 other side of the body at opposite sides of the bearing-slot 14 for the reception of a sliding plate or gate 17, arranged on the inner face of the adjacent side of the body and provided with an opening to receive the shaft and carried by the same. The plate 17 prevents water from escaping through the slot 14, and its lower portion fits in a socket 18 of the adjacent side of the body.

75 The pressure exerted on the clothes during 80 the operation of washing is obtained by means of springs 19, arranged adjacent to opposite sides of the body at each end of the shaft. The springs detachably engage hooks 20, arranged in pairs on the inner face of one side 85 of the body and the outer face of the other, and each spring consists of a central coil 21 and upward-diverging arms 22, which engage the hooks. The coil of each spring is arranged in a grooved disk 23, mounted on the 90 shaft. The groove of the disk is formed in the periphery thereof, and by this means the spring is strengthened and supported and is prevented from being injured. The grooved disks also form bearings for the journals of 95 the roller when the said journals move up and down in the ways of the washing-machine body, and the arms of the springs, which extend from opposite sides of the journals,

also serve to support them and to prevent a 5
jerky movement of the journals in the ways. The yieldingly-supported stationary rubber and the rubbing-cylinder are adapted to con-
5 form to the thickness of fabric and the quan-
tity of clothes passed between them to avoid
wearing, tearing, or otherwise injuring the
fabrics or being themselves injured.

The washing-machine body may be pro-
10 vided with any suitable construction of cover.

The octagonal rubbing-cylinder 10 consists
15 of two heads and a series of grooved slats or
bars secured to the peripheries of the heads
and projecting beyond the same, so as to lo-
cate the heads within the ends of the cylin-
der. The shaft consists of two journals ar-
20 ranged at the ends of the cylinder and pro-
vided at their inner terminals with securing
plates, and one of the journals is extended
outward beyond the body and has a crank-
handle secured to it.

It will be seen that the washing-machine is
simple and exceedingly inexpensive in con-
struction, that it is positive and reliable in
25 operation, and that the stationary rubber and
the rubbing-cylinder are yieldingly mounted
and are adapted to give to any increased
thicknesses of fabrics passing between them
30 to avoid injuring the fabrics or breaking the
machine.

Changes in the form, proportion, and the
minor details of construction may be resorted
to without departing from the principle or
sacrificing any of the advantages of this in-
35 vention.

What I claim is—

1. In a washing-machine, the combination
of a body, transverse cleats secured to the
body at the ends thereof, located near the
40 bottom of the same and provided at their ter-
minals with vertical recesses extending down-
ward from their upper edges, transversely-
disposed curved springs secured to the faces
of said cleats and having short end portions

spanning the recesses and capable of upward 45
and downward movement, and a rubber pro-
vided at opposite sides with depending longi-
tudinally-disposed strips having their ends
resting upon said springs and guided in the
said recesses and held against lateral move- 50
ment by the same, substantially as described.

2. In a washing-machine, the combination
of a body provided at opposite sides with ver-
tically-disposed slots having ways at one side
arranged at opposite sides of the adjacent 55
slot, a stationary plate 15 secured to the outer
face of the outer side of the body and closing
the adjacent slot, a vertically-movable plate
arranged in the said ways and closing the ad-
jacent slot, a removable rotating rubber pro- 60
vided with journals, one of the journals be-
ing loosely arranged in the slot adjacent to
the stationary plate, and the other journal
passing through a perforation of the verti-
cally-movable plate and carrying the latter 65
with it, grooved disks provided with bearing-
openings and mounted on the said journals,
permitting a free rotation of the same and
located at the inner face of one side of the
washing-machine body and at the outer face 70
of the other, springs comprising oppositely-
disposed arms extending outward from the
journals, and central coils formed integral
with the arms and arranged in the grooves of
the disks, whereby the springs are adapted 75
to force the rubber downward without bind-
ing against the journals thereof, and inverted
hooks mounted on the washing-machine body,
engaging the arms of the springs and detach-
ably securing the same to the body, substan- 80
tially as described.

In testimony that I claim the foregoing as
my own I have hereto affixed my signature in
the presence of two witnesses.

EDWIN KAIN.
